UNITED STATES PATENT OFFICE

MARCUS B. BEHRMAN, OF NEW YORK, N. Y., ASSIGNOR TO AMERICAN SAFETY RAZOR CORPORATION, OF BROOKLYN, NEW YORK, A CORPORATION OF VIRGINIA

RAZOR

Application filed September 13, 1927. Serial No. 218,207.

My present invention relates generally to razors, and has particular reference to a safety razor holder primarily designed for use with double-edged wafer type blades.

5 It is one object of my invention to provide a holder which is particularly applicable for employment with exceptionally narrow blades; and to provide a holder with which a magazine, for holding a supply of such 10 blades, may be associated. More particularly, it is an object to provide a holder with which a blade-holding magazine may be removably and frictionally associated in normally concealed position, and wherein a blade 15 seat is provided of a suitable size for accommodating thereon a selected blade.

Another object of my invention is to provide a razor holder wherein the employment of a double-edged blade will efficiently protect the unused edge thereof without any accompanying contact with said unused edge.

Another object is to provide a holder for a double-edged blade wherein the construction and arrangement are such that the proper 25 positioning of the blade upon a blade seat is accomplished by means other than pushing the blade transversely to the cutting edge.

It is a particular object to provide a blade seat whose structural nature is such as to 30 make use of the blade characteristics resulting directly from the manufacture of the blade. More particularly, it is an object to provide a seat which is so configured as to cooperate, for the proper positioning of the 35 blade thereon, with the configurations produced upon the completed blade in the course of the manufacture and processing of said blade.

It is an important object of my invention to 40 provide a holder which is extremely compact, more particularly one wherein the employment of the exceptionally small blades is accomplished by means of a correspondingly small blade seat.

45 Another object is to provide a holder whose constituent parts are arranged in normally inseparable relationship, thereby providing a unitary structure whose employment is not accompanied by repeated assembly and dis- 50 assembly of parts.

It is a feature of my invention to provide a blade seat, a handle whose upper end is beneath the seat, a blade cover which is devoid of any portions extending through the seat but which is provided with a portion extending around and thence beneath the seat, and means for releasably engaging the handle with the cover. 55

It is another feature of my invention to provide this structural arrangement in association with a hinged cover, the hinging serving to retain the cover in normally inseparable association with the device as a whole. 60

Another feature of my invention resides in providing means for retaining the handle in 65 similar normally inseparable association with the device as a whole. And it is a feature to provide the handle-holding means in such a manner that free movability of the handle is still rendered possible for effecting 70 the releasable engagement referred to. 75

A further feature of the invention resides in combining the foregoing features with the provision of a handle which is hollow or which is provided with a compartment for 75 the accommodation of the blade-holding magazine.

Other features of my invention reside in the provision of an arrangement for engaging the blade upon the seat by a contact over only a 80 substantially medial portion of the blade; an arrangement for efficiently enclosing, without contacting, the unused edge of the blade so engaged; an arrangement for rendering the width of the uppermost portion of the holder 85 substantially no greater than the width of the relatively narrow blade seat; an arrangement for permitting the application of a user's finger to the holder directly behind the blade seat so as to enhance the guidability of the device; and other arrangements which lead to 90 the provision of an extremely efficient, compact, simply constructed, easily operable, and attractively appearing razor holder. 95

For the attainment of the foregoing objects and such other objects as may hereinafter appear or be pointed out, I have illustrated one embodiment of my invention in the accompanying drawings in which—

Figure 1 is a perspective view of the razor 100

holder in association with a blade and ready for use;

Figure 2 is a side view on a slightly enlarged scale, showing the blade cover thrown back;

6 Figure 3 is a plan view of Figure 2;

Figure 4 is a view taken in the same direction as Figure 2 but shown in cross-section, and showing the blade cover in closed position;

10 Figure 5 is a cross-sectional plan view taken substantially along the line 5—5 of Figure 4; and

15 Figure 6 is an exploded view of the lower end of the handle, together with a blade-holding magazine designed for accommodation therein.

I provide a base 10 whose upper surfaces are angularly disposed and comprise a forwardly inclined portion 11 and a rearward surface 12 extending downwardly from the rear edge of the surface 11 at substantially right angles thereto. The surface 11 is constructed to constitute a blade seat and is inclined forwardly a slight degree as shown in 20 Figure 2. An undercut recess 13 is provided in the base to underlie the rear portion of the seat 11, and the bottom of the recess 13 is provided with an opening 14 to permit the passage therethrough of the upper threaded portion 15 of the handle. It will be noted that the handle in this way underlies the rear portion of the seat 11.

25 Hinged to the rear lower portion of the base 10, i. e., immediately to the rear of the opening 14, is a blade cover 16 comprising an angular member having a blade-covering portion 17 adapted to overlie the seat 11 when the cover is closed and a rear portion 18 extending from the rear edge of the portion 17 to the hinge 19. Arranged on the interior of the portion 18 is an attaching lug 20 having an internally threaded opening adapted to register with the opening 14 when the blade cover is closed and to receive the threaded end portion 15 of the handle. The lug 20 is designed to move into and out of the recess 13 when the blade cover is pivotally moved from the position of Figure 2 to that of Figure 4 and vice versa. Accordingly, the upper wall of the recess 13 is curved as shown most clearly in Figure 4, and the upper surface 21 of the lug 20 is also curved, these curvatures being substantially of a character whose center is at the 30 pivot axis 19. The base of the recess 13 is substantially flat, and the base 22 of the lug 20 is also flat so that this base may register with the base of the recess, as shown in Figure 4, when the blade cover is in closed position.

35 Before proceeding to describe in greater detail the features of the blade cover and the seat, I will describe the handle and the construction which retains it in permanent association with the device as a whole, while at 40 the same time permitting manipulation there-

of for effecting a releasable engagement of the cover.

A sleeve or tubular element 23 is attached below the base 10, this attachment being preferably accomplished by means of screw

70

threads 24. Mounted within the sleeve in a reciprocable and freely movable manner is the portion 15 already referred to, this portion being securely attached, by means of a bolt 25, to the main portion 26 of the handle. The handle, including the threaded portion 15 is therefore freely rotatable to effect the screw-threaded engagement between the handle and the lug 20. The handle must also be reciprocable, so that the upper end thereof may be withdrawn from the recess 13 during the releasable engagement referred to.

75

This reciprocal movement is rendered possible by the free mounting of the portion 15 in the sleeve 23, but this reciprocal movement is limited in extent so that the handle may

80

never be totally separated from the base 10, whether it is in engagement with the blade cover or not. The limitation of the reciprocal movement may be effected by providing

85

an abutment or internal shoulder 27 in the lower portion of the sleeve 23, and by providing an abutment or shoulder 28 between the main handle 26 and the sleeve 23. Thus, it will be noted that the lower portion of the handle portion 15 is provided with a shoulder which encounters the abutment 27 when the portion 15 is moved downwardly; and the upper portion of the handle 26 is so constructed as to encounter the abutment 28 when the handle is moved upwardly. In

90

Figure 2, the handle is in withdrawn or downward position; and in Figure 4, the handle is shown in its engaging or upward position.

95

Referring now more particularly to Figure 3, it will be noted that the seat is provided with the usual forward guard portion 29. The seat is designed to accommodate a double-edged blade of the flexible wafer type, the forward edge being held in proper positional relationship over the guard 29, and the rear or temporarily unused edge lying over the rear portion of the seat 11. Although, as to certain phases of my invention, the method of properly positioning such a blade upon

100

the seat is immaterial, I have illustrated and shall now describe a construction which avails itself of the configurations formed

105

upon the blade during the manufacture and processing thereof. The blade I have illustrated is provided with a medial ridge or rib 30, this rib having a definite function during

110

the manufacture of the blade. At the opposite ends of the rib, recesses 31 are provided. It will be noted that the blade is an excep-

115

tional narrow one.

120

The seat 11 is provided with a medial raised portion 32 and lugs or projections 33 at the

125

opposite ends thereof, the portions 32 and 33 being so constructed and arranged that any

130

selected blade may be applied thereto and will be automatically positioned in proper relationship to the guard by virtue of the fact that the rib 30 will accommodate itself upon the complementary raised portion 32, and the recesses 31 will accommodate themselves about the conformably constructed and arranged lugs 33.

The function of the blade cover is to hold the blade in such proper position by a pressure applied thereto from above. Upon reference to Figures 2 and 4, it will be noted that the portion 17 of the blade cover is interiorly concave, and that by virtue of this construction only the forward edge of the portion contacts with the blade 34 which has been applied to the blade seat. This contact occurs at a medial portion of the blade 34, leaving the forward operative edge entirely free for shaving purposes, and the cover portion 17 extends upwardly and rearwardly away from the line of contact so as to enclose, without contacting, the rear and temporarily unused edge of the blade 34. The manner in which this rear edge is enveloped and thereby protected is clearly shown in Figure 4.

It will be noted also that the portion 18 of the blade cover is exteriorly concave, and this configuration permits the user to apply his forefinger thereto in a convenient manner so as to enhance the guidability of the device by a pressure applied directly behind the blade.

It will also be noted that the cover portion 16 is laterally flanged as at 35 (Figures 3 and 5), and these flanges render the assembled and closed device particularly efficient and attractive, inasmuch as they enclose the lateral edges 36 of the base 10, and also the lateral edges of the blade being employed. The advantageous functioning of the flanges 35 is clearly shown in Figure 1.

When the device is employed, the handle is manipulated to release the lug 20, and the blade cover is thereupon free to be swung backwards into the position of Figure 2. A selected blade is then applied to the blade seat 11, positioning itself thereon in an accurately predetermined relationship with respect to the guard 29. Thereupon, the blade cover is swung forwardly into the position of Figure 4. This encloses the blade (with the exception of the operative edge thereof) and it also positions the attachment lug 20 directly over the upper threaded end of the handle portion 15. The handle may then be manipulated to screw the portion 15 into the lug 20 and thereby present an assembled and completely set-up device for operation. In the changing of blades, or the cleaning of the device, the operations are reversed, as will be readily understood. It will be noted that the cover is held in closed position by a releasable engagement taking place beneath the seat. This is effected despite the absence

of any perforations in the seat and any corresponding perforations in the blade through which attaching lugs or the like would have to project. It will also be noted that the tension of the handle upon the closed cover is in a direction substantially perpendicular with respect to the seat. This construction and arrangement renders the device as a whole peculiarly compact and highly attractive, at the same time permitting the blade seat 11 to be of an extremely small size, having no greater width than that of the blade being employed. As a result, the overall width of the upper portion of the assembled device is reduced to a minimum, thereby permitting the device to be employed with great efficiency upon even the most inaccessible portions being shaved.

Another feature of my invention resides in the provision of a compartment in the handle within which a blade-carrying magazine may be frictionally and removably accommodated. I have shown the main portion 26 constructed with an octagonal cross-section, and of a tubular nature, having its lowermost end open. A conformably constructed cap 37 is applicable over this open end and is provided with a flat under-surface 38 which permits the assembled device to be stood on end as shown in Figure 1.

In Figure 6 I have illustrated the type of blade-holding magazine which may be advantageously employed. The magazine illustrated is constructed for use primarily with blades of the character described, and comprises two opposite parallel sides 39 spaced by a distance only slightly greater than the width of the blade. At the opposite ends of the magazine, upstanding lugs or fingers 40 are designed to accommodate themselves in the recesses 31 of a set of stacked blades. The size of the hollow handle and the size of the blade magazine are so co-related that the latter may be frictionally inserted and removed from the handle, the sides bracing themselves against opposite parallel sides of the octagonal handle. It will be understood that an octagonal shape is by no means essential, the essence of the construction being that the magazine-accommodating compartment is conformably constructed with respect to the magazine so that the latter may be removably accommodated.

It will be understood that certain phases of my invention do not limit me to the employment of the particular type of blade illustrated and described. The seat may be constructed in other ways for accommodating, in a similarly efficient manner, blades which have configurations embodied thereon. In general, the details herein described and illustrated for the purpose of explaining the nature of my invention may be changed by those skilled in the art without departing from the spirit and scope of the invention.

as expressed in the appended claims. It is therefore intended that these details be interpreted as illustrative, and not in a limiting sense.

Having thus described my invention and illustrated its use, what I claim as new and desire to secure by Letters Patent is—

1. In a razor holder, a sleeve member, a substantially cylindrical hollow base mounted upon said sleeve member coaxially with the latter, a blade seat arranged transversely across the front half of the upper end of said base to provide a recess beneath the rear half of said seat, said seat being adapted to receive a razor blade thereon, the rear half of said base being cut away, a blade seat cover pivoted to said base at the rear lower end of the cutaway portion and below the plane of the blade seat, a threaded lug carried by said cover and movable into and out of said recess when the cover is pivoted, and a handle reciprocally and rotatably mounted in said sleeve member and having an upper threaded end projectable upwardly into said base and into threaded engagement with said lug to hold the cover closed.
2. In a razor holder, a sleeve member, a substantially cylindrical hollow base mounted upon said sleeve member coaxially with the latter, a blade seat arranged transversely across the front half of the upper end of said base to provide a recess beneath the rear half of said seat, said seat being adapted to receive a razor blade thereon, the rear half of said base being cut away, a blade seat cover pivoted to said base at the rear lower end of the cutaway portion and below the plane of the blade seat, a threaded lug carried by said cover and movable into and out of said recess when the cover is pivoted, and a handle reciprocally and rotatably mounted in said sleeve member and having an upper threaded end projectable upwardly into said base and into threaded engagement with said lug to hold the cover closed, said cover being so shaped that, when it is closed, only its forward edge will bear downwardly upon a forward portion of a blade upon said seat to hold said blade in position thereon.

In witness whereof, I have signed this specification this 2nd day of September, 1927.

MARCUS B. BEHRMAN.
